LOCK

Herman F. Schmidt, San Antonio, Tex.

Application December 11, 1934, Serial No. 757,039

2 Claims. (Cl. 292—246)

The invention relates to a lock and more especially to a door or window lock.

The primary object of the invention is the provision of a lock of this character, wherein the construction thereof is such as to permit its use on sliding or swinging windows or doors, so that these may be locked to avoid outside intrusion, it being practically impossible to release the lock from the outside of an enclosure and such lock will maintain the door or window firm to avoid any rattling action thereof.

Another object of the invention is the provision of a lock of this character which is simple in construction, thoroughly reliable and efficient in its purpose, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

25 Figure 1 is a fragmentary vertical sectional view through the upper and lower sashes of a window, showing the lock constructed in accordance with the invention applied thereto, the lock being shown by full lines in locking position and by dotted lines in releasing position.

Figure 2 is a fragmentary horizontal sectional view showing the lock in plan.

Figure 3 is a horizontal sectional view through the lock.

35 Figure 4 is a vertical transverse sectional view through the lock.

Figure 5 is another vertical transverse sectional view through the lock.

40 Figure 6 is a vertical longitudinal sectional view through the lock.

Figure 7 is a plan view of the keeper base.

Figure 8 is a plan view of the base of the lock casing.

45 Figure 9 is a plan view of the blank from which the casing is made.

Figure 10 is a horizontal sectional view showing a slight modification of lock.

Figure 11 is a sectional view on the line 11—11 of Figure 10.

Figure 12 is an elevation of the keeper of the modified form.

Figure 13 is a view similar to Figure 10, showing a slight further modification.

55 Figure 14 is a sectional view on the line 14—14

of Figure 13, looking in the direction of the arrows.

Figure 15 is a perspective view of the keeper, the same being inverted.

Similar reference characters indicate corresponding parts throughout the several views in the drawings.

Referring to the drawings in detail, particularly Figures 1 to 9 which disclose the preferred embodiment of the invention, A designates a part 10 of an upper sash and B a part of the lower sash of a window, these being of standard make-up, and upon the top meeting rail of the lower sash is the base plate 10 of the lock casing 11, the latter being cut from a single blank to provide 15 a top, sides and ends, the sides and ends being formed with the lugs 12 which fit in suitable openings 13 in the base plate 10 and being riveted or otherwise made secure so that the base plate 10 and the casing become a unit. Fitted within the casing 11 is a slide block 14 through which is passed 20 a plunger 15, the same being secured to the block by a tie pin 16 and this plunger works through suitable openings 17 in the ends of the casing 11. At the outer end of the plunger 15 is a hand knob 25 or head 18, while the inner end 19 of the said plunger constitutes an auxiliary lock operating in a manner presently described.

The base plate 10 is made secure to the top cross rail of the sash B by fasteners 20. The block 30 14 has swingingly fitted therein the ends of a main locking loop or yoke 21, the sides of the casing 11 being cut away as at 22 to provide a clearance for the said loop or yoke 21.

Carried by the bottom meeting rail of the upper 35 sash A is the keeper 23, this being joined with the base 24 suitably secured to the sash, and releasably engageable with the keeper 23 is the loop or yoke 21. The keeper 23 is provided with the socket 25 for the end 19 of the plunger 15, as will 40 be apparent in Figure 3 of the drawings and thus it can be seen that a double lock is had with the keeper 23. Surrounding the plunger 15 and tensioning the block 14 is a coiled expansion spring 26 which when compressed permits the disengagement of the loop or yoke 21 from the keeper 23 and also the release of the end 19 from the said keeper 23. Normally the spring 26, under the tension thereof against the block 14 when the yoke or loop 21 is engaged with the keeper 23, 50 holds the said yoke or loop under tension so as to prevent rattling of the sashes A and B within the window frame. It should be apparent that any unevenness in the meeting relation of the meeting rails of the sashes A and B will not in any 55

manner disturb the locking of the sashes in the use of the lock as hereinbefore described. It is practically impossible to release the lock from without an enclosure and such lock can be released from within the enclosure with ease and dispatch.

In Figures 10 and 11 of the drawings there is shown a slight modification of lock, wherein the casing 27 has mounted therein a guide 28, over which is telescoped the tubiform plunger 29 having the hand knob or head 30, this plunger 29 being threaded into the slide block 31 mounted within said casing 27, while surrounding the guide 28 is the tensioning spring 32, this operating upon the slide block 31 alike to the spring 26.

The slide block 31 carries the swinging yoke or loop 33 engageable with the keeper 34, the latter being upon a door frame 35 while the casing 27 is upon a swinging or sliding door 36.

In Figures 13 and 14 of the drawings there is shown a still further modification of the invention, wherein the lock casing 37 has the sliding block 38 therein and threaded into this block is the plunger stem 39 carrying the hand knob or head 40 and operative against the block 38 is the tensioning spring 41, the block being fitted with the swinging yoke or loop 32 engageable with the keeper 43 secured upon a base 44.

It appears needless to describe in detail the operation of the lock because from the drawings such operation should be apparent, both in the locking and unlocking action.

In the use of the lock a door or window can be firmly secured to avoid rattling of the moving

parts thereof and to avoid any possibility of the jimmying of the lock from without so that it is practically impossible to release the lock from without an enclosure.

The parts of the lock are simple and the assembly thereof compact, with resultant strength and durability.

What is claimed is:

1. The combination of a casing having a top, bottom, perforated ends, and slotted sides, a block 10 slidable in the casing, a keeper, a loop-like bail for engaging the keeper and having ends passed through the slotted sides and swingingly seated in the block, a spring within the casing and active upon the block for urging the bail in locking engagement with said keeper and a push plunger engaged in the block and guided through one perforated end of the casing for external gripping thereof.

2. The combination of a casing having a top, bottom, perforated ends, and slotted sides, a block slidable in the casing, a keeper, a loop-like bail for engaging the keeper and having ends passed through the slotted sides and swingingly seated in the block, a spring within the casing 25 and active upon the block for urging the bail in locking engagement with said keeper, a push plunger engaged in the block and guided through one perforated end of the casing for external gripping thereof and a guide for said plunger and 30 having a fastener engaged in the other perforated end of the casing.

HERMAN F. SCHMIDT.
